Geo. N. Goddard, Atty.

UNITED STATES PATENT OFFICE.

WALTER BIXBY, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

SUPPORTING MEANS FOR TUBE-FRAME SPOOLS.

Application filed March 7, 1923. Serial No. 623,524.

To all whom it may concern:

Be it known that I, WALTER BIXBY, a citizen of the United States, and resident of Boston, in the county of Suffolk and State 5 of Massachusetts, have invented certain new and useful Improvements in Supporting Means for Tube-Frame Spools, of which the following is a specification.

This invention relates to tube frames for 10 weaving and is intended to provide a simple and convenient construction for mounting the yarn spool in the tube frame in such manner as to permit its quick and convenient insertion and replacement.

15 It is customary in constructing tube frames for use on the wider looms to make the yarn spool in two or more sections placed end to end with the journals of each section either telescoping one into another, 20 or else having a butt end contact between two adjacent journals each of which occupy a portion of the length of the bearing recess, and it has been common practice to make a split or separable bearing one part 25 of which is movable away from the other to allow the spool journals to be inserted or taken out.

The present invention, while not precluding the use of a split bearing, is primarily 30 intended to make possible and convenient the use of an integral instead of a sectional bearing box, provision being made for the instant and convenient insertion of each spool section as well as for its quick removal.

35 To this end the invention comprises generally in combining with the carrier bar and the yarn spool, a bearing bracket member supported by the former in position to afford bearing support for adjacent ends of 40 the spool sections and mounted to permit movement toward and away from the end of one spool section whereby, after the spool journal is inserted, it may be returned to normal operative position to afford bearing 45 for said spool section and its adjacent section. This and other features of the invention will be more particularly described in the following specification and will be defined in the claims forming part thereof.

50 In the drawings I have illustrated several forms of construction and arrangement embodying the principles of this invention, in which:

Figure 1 is a front elevation of a tube

frame with intermediate parts broken away 55 to shorten its length.

Figure 2 is a cross sectional view showing the movable bearing bracket in operative position.

Figure 3 is a detail view in front elevation showing the movable spool-supporting bracket.

Figure 4 is a side elevation of the same.

Figures 5 and 6 are similar views of modified forms of construction. 65

Figures 7 and 8 are corresponding views of another modified construction of the spool-supporting bracket.

Figure 9 is a detail perspective view showing the fulcrum or attaching member for the 70 bracket shown in Figures 7 and 8, and

Fig. 10 is a horizontal sectional view of the structure of part 36 of Fig. 7.

In the practice of this invention, according to the form illustrated in Figure 1, the 75 carrier bar 1, is provided with the usual suspension hangers 2, by which it is suspended from the overhead carrier chains which deliver it to the transfer mechanism for use in the looms. Along the front face of the 80 carrier bar 1, is mounted a series of individual tuft needles or guide tubes through which the yarn from the spool is delivered to the fabric in the weaving process. The rigid suspension hangers 2, are provided 85 with upwardly extending ears 2^a which afford bearings for the journals 5 and 6 of the yarn-spool sections 4.

According to the illustration of the drawings, one journal 5 is a fixed or rigid journal projecting into the bearing ear 2^a, while the other journal 6 is a telescoping spring-pressed journal mounted in a recess 4^a in the spool so as to be pressed inwardly to allow its insertion into the closed bearing ear 95 2^a. At their adjacent end, the two interlocked spool sections are provided, respectively, with journals of any suitable construction which, in this case, are shown as comprising a journal 7 provided with a mortised recess 7^a adapted to receive the tenon 8 of the yarn journal or gudgeon of the adjacent section in order to secure unison in rotation as the yarn unwinds. In this case, as the gudgeon 8 telescopes inside of the 105 journal or gudgeon 7, the bearing which supports the adjacent ends of the spools is made of a size to fit around the gudgeon 7 but, ob-

viously, it forms a support for the adjacent ends of both spools.

The supporting member or bearing bracket in this case is shown as an arm or

5 plate 9 provided with a cylindrical bearing aperture 9^a and hingedly connected to a foot piece or attaching member 10 by means of a pivot pin 11 so as to allow lateral movement of the bearing arm away from the ad-

10 jacent end of the left hand spool to the position indicated in dotted lines in Figures 1 and 3. The attaching member 10 may be secured to the carrier bar in any suitable manner as by fastening screws.

15 In Figure 1 it will be observed that the hinged bearing arm 9, has attached to one side an angular spring arm 12, which normally exerts a tension to keep the arm in vertical position although yielding suffi-

20 ciently to allow the arm to swing away from the head of the left hand spool. A counter-spring or bracket 13, is located on the opposite side to prevent the bearing bracket from swinging beyond its proper

25 position for service. By this arrangement the bearing arm is capable of a slight automatic adjustment to accommodate it to the rotating spool journal while normally returning it to operative position after it has

30 been laterally misplaced for the insertion of a spool section.

The modification shown in Figures 5 and 6 illustrates a simpler form of hinged connection for the bearing bracket 20 as the

35 bracket is provided with a transverse slot 21 which receives a hooked shaped plate 22

employed as an attaching member in lieu of

the looped eye plate 10 and pin 11.

40 In Figures 7 and 8 the bearing arm is shown formed of a single piece of pressed steel folded upon itself lengthwise to form

45 parallel integrally united arms 30, the middle portion of the strip forming these arms being bent into the form of an eye 31 pass-

45 ing around a pivot pin 32 which is held in position by an attaching eye plate 33, shown

50 in perspective in Figure 9. As therein shown, the curved portion of an eye plate 33 is struck up to form stop lugs or lips 34,

55 to limit the swinging movement of the arm. A coiled spring 35 placed around the pivot pin 32 acts to normally but yieldingly maintain this bracket in vertical position. A bearing bushing 36 is inserted in the regis-

55 tering apertures in the two arms 30 of the bracket to afford a cylindrical bearing for the spool journal and also to hold the two arms firmly together at their upper ends.

What I claim is:

60 1. In a tube frame for weaving, the combination of a longitudinal tube-carrying bar, spool-supporting members secured to opposite ends of the carrier bar, a sectional yarn-spool rotatably supported at its outer ends in bearings in said supporting members, one

or more intermediate spool-bearing brackets mounted on said tube-carrying bar in position to normally support adjacent ends of the spool sections, said bearing bracket being movable out of normal position for insertion of a spool section, and a bracket-engaging spring arranged to yieldingly restore said bracket to normal operative position, substantially as described.

2. In a tube frame for weaving, the combination of a spool-supporting frame comprising a longitudinal carrier bar and spool-supporting end brackets, an intermediate pivotal bracket provided with a closed bearing for supporting adjacent end sections of a yarn-delivering spool, means for limiting the pivotal movement of said bracket in one direction, and means for yieldingly opposing its movement in the other direction, and a sectional spool rotatably supported in said intermediate and end brackets, substantially as described.

3. In a tube frame for tuft weaving, the combination with a carrier-bar, of a yarn-spool operatively mounted thereon and comprising longitudinal sections arranged end to end to rotate in unison to deliver yarn, a bearing bracket mounted on said carrier-bar with its spool-bearing portion interposed between the adjacent ends of two spool sections to operatively support the spool sections, and movable away from one of said spool sections to allow its removal and replacement, and means for automatically returning said bearing bracket to operative position, substantially as described.

4. In a tube frame for tuft weaving, the combination of a carrier-bar, of a yarn-spool mounted thereon, said spool comprising end to end sections rotatable in unison to deliver yarn, one of said sections being mounted at its opposite ends in closed bearing brackets, the inward bearing bracket being movable away from said spool section by lateral pressure to permit withdrawal or insertion of the spool, and means for automatically returning said movable bracket to and maintaining it in normal operative bearing position, substantially as described.

5. In a tube frame for tuft weaving, the combination with a carrier-bar, of a yarn-spool rotatably mounted thereon to deliver yarn, a pair of spool-supporting bearing brackets supporting the opposite journals of said spool in closed bearing brackets, one of said bearing brackets being movable away from said spool, under lateral pressure, and bracket-engaging spring and stop members arranged to normally maintain said movable bracket in operative bearing position, while allowing it to be moved to spool-removing position, substantially as described.

6. In a tube frame for tuft weaving, the combination with a carrier-bar, of spool sections co-axially mounted thereon to permit

rotation for the delivery of yarn, a pivotal bearing bracket interposed between the adjacent ends of two spool sections and mounted to swing about an axis transverse to said carrier-bar, a spring arranged to yieldingly maintain said bracket in normal bearing position, and a stop member arranged to oppose and limit the spring-actuated pivotal movement of the said bracket to prevent endwise pressure of the bracket against its supported spool section, substantially as described.

7. In a tube frame for tuft weaving, the combination with a carrier-bar, of a rotatable sectional yarn-spool whose sections are arranged end to end, an intermediate bearing bracket movable away from one spool section to permit its removal and normally pressed toward said spool section by a yielding spring, and a stop member ar-

ranged to limit the pivotal movement of said bracket whereby the bracket is normally maintained in and restored to operative position without exerting axial pressure on either adjacent spool section, substantially as described. ²⁵

8. In a tube frame for tuft weaving, the combination with a longitudinal carrier-bar, of a sectional yarn-spool rotatably supported thereon, an intermediate bearing bracket interposed between two adjacent yarn-spool sections and comprising parallel plates secured together side by side, and a bearing bushing inserted through registering apertures in said plates to support the spool- ³⁰ journals, substantially as described. ³⁵

In witness whereof, I have subscribed the above specification.

WALTER BIXBY.
